TABLE TOP

Ernest Richardson, Beaver Falls, Pa., assignor to
Ingram-Richardson Mfg. Company, Beaver
Falls, Pa., a corporation of Pennsylvania

Application February 14, 1945, Serial No. 577,904

8 Claims. (Cl. 311—106)

1

This invention relates generally to improvements in the attachment of preformed porcelain enameled sheet metal to prefabricated frames and more particularly to the construction of porcelain enameled metal panels arranged for vertical or horizontal mounting on cabinets and tables, and the manner in which they are fitted and secured to prefabricated frames.

Although this invention is particularly adapted for use on single or multiple table panels, commonly known as kitchen tables, the principles are readily adapted for use in conjunction with cabinets, stands and other similar articles of furniture requiring porcelain enameled sheet metal walls, tops, faces and doors arranged to be secured to prefabricated frames made of any suitable material such as wood, plastic, steel and the like, wherein the combination of the sheet metal and the frame provide the desired rigidity of the article.

The principal object is the provision of a connection between a porcelain enameled steel facing and a frame which produces a strong, tight and continuous surface therebetween.

Another object is the provision of a joint between a porcelain enameled steel member and a frame member which reinforce each other providing a continuous surface losing the identity of the joint and providing a protection for the porcelain enameled steel.

Another object is the provision of a joint between porcelain enameled facing and a frame wherein the underside of the facing has continuous engagement on two sides of the frame and a cleat on the third side.

Another object is the provision of a series of cleats for anchoring a porcelain enameled facing to a frame.

Another object is the provision of a plurality of cleats formed integral with a preformed porcelain enameled facing and producing a series of open sockets to receive and connect with a frame.

Other objects and advantages appear from the drawings illustrating the invention and in the following description and claims.

A practical embodiment illustrating the principles of this invention is shown in the accompanying drawing wherein:

Fig. 1 is an enlarged isometric view partly in section showing a table top connected to a frame.

Fig. 2 is a view of the under side of the table top and frame shown in Fig. 1.

Fig. 3 is an isometric view partly in section showing a vertical panel connected to a frame.

2

Fig. 4 is a broken sectional view showing a modified form of a porcelain enameled table top and frame.

Fig. 5 is a sectional view of the table top shown in Fig. 4 with a different type of frame trim.

Fig. 6 is a plan view of the frame and trim shown in Fig. 5 with parts broken away.

Referring to Figs. 1 and 2 of the drawing the table top or facing panel 10 consists of a preformed steel sheet having a porcelain enameled coating which may be plain or suitably decorated in colors. The preformed table top 10 is provided with a perimetral depending flange 11 of uniform depth which joins the body of the top with a radius of curvature 12 that is shorter than the depth of the flange to provide a purchase surface 13 in a plane normal to the table top. At spaced intervals the under side of the table top has a series of spaced cleats or angle brackets 14 which are welded thereto prior to the formation of the porcelain enameled surface. The vertical leg 15 of each angle bracket is provided with at least one hole to receive a fastening screw 16 and is gauged relative to the purchase surface 13 of the flange 11 to form a socket between the adjacent surfaces of these members and in which the frame 17 of the table is received. The frame 17 illustrated in Fig. 2 is rectangular in shape and is provided with the cross brace or support 18. If the frame is made of wood or steel it is prefabricated as a unit from five or more pieces matched at their connecting joints or the frame may be molded into an integral unit when made of a suitable plastic material. The brackets 20 and 21 are the same as the brackets 14 but are gauged relative to each other to provide a socket to receive the cross brace 18 therebetween.

The perimetral edge of the frame 17 is provided with a mating curvature and offset 22 to receive the inner curved surface and the purchase surface 13 of the flange 11 in continuous surface engagement. A small clearance is preferably provided between the bottom edge of the flange 11 and the shoulder of the offset 22 to insure engagement between the under side of the table top and the upper surface of the frame 17. However the shoulder of the offset 22 is equivalent in width to the thickness of the porcelain enameled steel to provide a smooth and substantially continuous surface at the joint between the exterior of the flange 11 and frame 17 as shown.

To prevent the porcelain enameled surface on the flange 11 from being struck or bumped, the frame 17 is provided with a perimetral protruding edge 23 which in Fig. 1 is shown as a round-

ed section or molding forming the table edge trim. This trim extends upwardly to the shoulder of the offset 22 by a reverse curved surface 24. This structure eliminates the objectionable sharp table corners and provides a smooth joint that is well protected and exceptionally strong owing to the fact that the mating surfaces of the table top and frame are in continuous contact for the full extent of their overlying or matched surfaces. This is an important object of this invention.

The joint between the vertical wall or panel member 25 and the frame 26 as shown in Fig. 3 is similar to the table top structure of Figs. 1 and 2 as the under surface and the purchase surface 13 of the flange 11 mate in continuous contact with the upper surface and offset 22 of the frame 26. However the angle bracket 27 that is welded to the panel 25 must be formed with a double angle and intermediate section 28 to extend the continuous engagement across the top of the frame 26 to the vertical leg 29 which section completes the socket for receiving the frame. The leg 29 of the bracket is provided with a hole for the fastening screw 16. In this manner the connection between the frame and the vertical panel is provided with the same attributes as that of the table top and frame connection of Figs. 1 and 2.

The modification shown in Fig. 4 consists of a table top or panel member 30 having a perimetral edge in the shape of a channel section providing an inturned flange 31. This structure requires an offset 32 having a broader shoulder in the frame 33 and the edge of the inturned flange 31 engages the vertical face of the offset. A slight clearance is provided between the bottom of the inturned flange and the shoulder of the offset to insure engagement between the under surface of the member 30 and the upper surface of the frame. The channel section is out of engagement with the offset except at the line of purchase along the edge of the inturned flange 31 which is spaced from the table top. Closer tolerances may be provided in gauging the vertical leg 45 of the bracket 14 from the purchase edge of the inturned flange 31 to form the socket as the resiliency of the channel section and the angle bracket permit tight engagement of the frame when the latter is mounted in the socket.

The modification of Fig. 5 differs very little from that shown in Fig. 4 insofar as the connection between the table top or panel member 30 and the frame 35 is concerned. The change in this structure resides in the provision of a metal trim 36 around the perimetral edge of the frame 35. The trim 36 is preferably made of a highly polished stainless or chrome steel and is provided with the inturned tongues 37 which rest on the shoulder of the shallow pockets 38 in the frame 35. The trim extends downwardly and outwardly as shown at 40 and 41 to provide an offset to receive the inturned flange 31 the edge of which engages the vertical portion 40 of the trim 36 and sufficient clearance is provided between the flange 31 and the horizontal section 41 of the trim to permit the under surface of the panel member 30 to engage the top of the frame 35. The trim 36 then projects outwardly beyond the panel 30 and returns to the under side of the frame and is secured by any suitable means as the screws 12.

In each instance the frame receiving sockets formed by the structures of Figs. 1 to 5 are open

and unobstructed. When properly gauged they slip snugly over the frame and the mating surfaces engage, particularly between the under-side of the panel and the top surface of the frame. When properly assembled the screws 16 maintain the purchase surface of the flange against the counter part of the frame. This improved joint provides a tight and firm connection between porcelain enameled sheet and the frame even though it extends along only one edge of the panel. When employed as a table top connection around the full perimeter of the panel the gripping forces acting through the purchase surfaces on opposite sides thereof react against one another as well as against the angle brackets to produce a solid and substantial table.

When the frame is a continuous annular support for the panel 30 in Fig. 5 the screws 42 are not required to secure the trim 36 to the frame as the annular series of spaced tongues 37 support the trim 36 in position when they are bent over to engage the shallow pockets 38 in the outer top edge of the frame. If the panel surface is rectangular in shape the corners of the panel 30 and the frame 35 are rounded and the tongues 37 are placed at the corners and at spaced intermediate positions between the corners. Again if the panel surface is circular the tongues 37 and the pockets 38 are uniformly spaced about the perimeters of the members.

The open frame receiving sockets on the under side of the porcelain enameled steel panels are readily mounted on their prefabricated frames and since the whole of the surface of the panels is coated with porcelain enamel any moisture between the engaging surfaces of the panel and the frame will not rust the former. Thus surface engagement between the panel and the frame is not detrimental due to moisture and a firm and inflexible connection is provided which permits the use of lighter gauge sheet metal than possible with similar structures known in the art.

I claim:

1. In a porcelain enameled panel to frame connection the combination of a panel member having a flat surface adjacent one side, a flange formed on said side and below the flat surface, an angle bracket secured to the panel member and having a depending portion set at a gauged distance from the flange to form an open socket with the under side of the flat surface and the flange, a frame having top and side surfaces arranged to fit the socket and to mate in surface engagement with the under side of the flat surface and the opposed surfaces of the flange and the depending portion of the angle bracket, and means to secure the depending portion of the angle bracket to the frame and maintain the surface engagement of the panel and the frame.

2. The structure of claim 1 characterized in that the flange depends at right angles from the flat surface of the panel with a radius of curvature therebetween and a mating radius of curvature on the frame permitting continuous contact between the co-extensive portion of the panel and the frame.

3. The structure of claim 1 characterized in that the flange depends at right angles from the flat surface and the upper perimetral edge of the frame is provided with a mating offset to receive the flange and produce a flush surface between the side of the frame and the outer face of the flange.

4. The structure of claim 1 characterized in that the lower outer edge of the frame extends

beyond and below the perimeter of the panel to form an offset in the frame to receive the flange, and the flange and the offset being constructed to form a continuous surface of the panel and the frame edges.

5. The structure of claim 1 characterized in that the flange is inturned, an offset in the frame to receive and be engaged by the edge of the flange, and the flange and the offset being constructed to form a continuous surface of the panel and the frame edges.

6. The structure of claim 1 characterized in that the flange is inturned, a trim secured to the frame and having an offset to receive and be engaged by the edge of the flange, and the flange and the offset being constructed to form a continuous surface of the panel and the frame edges.

7. In a porcelain enameled panel to frame connection the combination of a panel member having a perimetral flat surface, a perimetral flange on the panel depending below the flat surface, an annular series of angle brackets secured in spaced relation to the panel member, each angle bracket having a depending portion set at a gauged distance from the flange section opposite thereto to form a series of open sockets with the under side of the perimetral flat surface and the flange, a continuous annular frame having

5 top and side surfaces arranged to fit the sockets and to mate in surface engagement with the under side of the perimetral flat surface and the opposed surfaces of the flange and the depending portions of the angle brackets, and means to secure each depending portion of the angle brackets to the frame and maintain the surface engagement of the panel and the frame.

8. The structure of claim 7 characterized in that the flange is inturned, an annular trim having an offset to receive and be engaged by the edge of the flange and extending beyond the perimeter of the panel with a return bend engaging the under side of the frame, a series of spaced 10 pockets in the outer top edge of the frame, and a series of tongues on the trim extending into 15 said pockets to secure the trim to the frame.

ERNEST RICHARDSON.
